UNITED STATES PATENT OFFICE.

AUGUST DICKMANN, OF FURTH, GERMANY.

POCKET GLASS.

Application filed March 23, 1925, Serial No. 17,740, and in Germany January 30, 1925.

This invention relates to a pocket-glass as funny article owing to the fact that when using the pocket-glass the observer sees a figure, a picture or the like passing over the reflecting surface of the glass. This effect is obtained by using the back wall of a flat box as reflecting surface, the front wall being made entirely or partly of transparent glass, a body being inserted in the low space between the two walls of the box and said body moving through the box according to the position in which the pocket-glass is held.

The transparent front wall of the box is preferably partly covered at the upper or lower end or at both ends by a piece of paper. The body enclosed in the box is not visible when the pocket glass is held in the vertical position and the hidden body will suddenly appear. A special effect is obtained when the covered parts of the front wall of the box are reflecting as in this case a continuous reflecting surface is obtained and it looks as if the body appeared in mysterious manner on the surface.

The movement of the enclosed body may be controlled in various manners.

A thin almost invisible thread may be used for limiting this movement so that the body stops for instance at the centre of the glass.

An embodiment of the invention is shown, by way of example, on the accompanying drawing in which—

Figs. 1 and 2 show respectively in front elevation or in vertical section a pocket glass in which the enclosed body drops by gravity.

Figs. 3 and 4 show respectively in elevation and vertical section a pocket glass, the front wall being removed in Fig. 3, in which the movement of the body is controlled by a weight.

Figs. 5 and 6 show respectively in front elevation and vertical section a pocket glass filled with a liquid. The specific gravity of the enclosed body is either slightly lighter or slightly heavier than that of the liquid, so that the body ascends or descends slowly over the reflecting surface.

In the pocket-glass shown in Figs. 1 and 2 the rear wall *a* and the front wall *b* are held at a convenient distance the one from the other by a strip of cardboard inserted between the edges. The rear wall *a* has on the outer surface a mirror foil *d* protected

by a cover *e* of paper, cardboard, leather or the like. The front wall *b* is transparent for its largest part. Only the upper part has on the rear side a mirror foil *f*. The two walls *a* *b* are mounted in a frame *g* of U-shaped cross section.

In the hollow space between the two walls *a* and *b* a body *h*, for instance a paper disk having a picture painted on it or a funny figure, is enclosed. This body *h* is suspended on a thin thread *i* which is scarcely visible.

When the pocket-glass is held upside down, as shown on the drawing, the body *h* is hidden behind the mirror foil *f*. The surface of the pocket glass looks like one single mirror surface. When the pocket glass is turned downside up the body drops and emerges suddenly from the reflecting surface. It is held in suspension by the thread *i*.

In the pocket glass shown in Figs. 3 and 4 the mirror foil *k* is on the inner surface of the rear wall *a* so that the rear side of the pocket glass is also reflecting. On the rear wall *a* a plate *l* of cardboard, wood or the like is placed on the lower part of the inner surface of the rear wall and on the upper part a piece of glass *n*, having a mirror foil *m* on the back is fixed. In the plate *l* a pin *o* is fixed on which a lever *p* is pivotally mounted. A counter weight *v* is fixed to one end of lever *p* and a short rod *r* is hingedly connected with the other end of the lever. A cross arm *t* at the upper end of the rod *r* carries the picture or figure. The front wall *b* of the mirror has on the lower part of its rear surface a mirror foil *f*, its upper part being transparent. The two walls are mounted in a frame *g* and spaced by a strip *c*.

When the mirror is held in the opposite direction as shown in Fig. 3 the dropping weight *v* pushes the rod *r* up so that the picture disappears behind the mirror foil *f*, the pocket glass seen from the front being one reflecting surface. As soon, however, as the pocket glass is held in the position shown in Fig. 3, the weight *v* pushes the picture up so that it is visible through the upper transparent part of the front wall.

In the pocket glass shown in Figs. 5 and 6 the space between the front wall *b* and the rear wall *a* is filled with water or another liquid and the body *h* enclosed between the two walls, the specific gravity of which is

lower than that of the water, floats in the water. Between the edges of the two walls a strip *u* of india rubber is arranged on which the glass plates are cemented by a cement insoluble in water. The pocket glass is otherwise constructed as shown in Fig. 1. The body *h* hidden behind the mirror foil *f* ascends slowly when the pocket glass is brought into the position shown.

10. The body *h* might also be of greater specific gravity than the liquid enclosed in the box in which case the body will descend instead of ascending.

15. The pocket glass may also be used for advertising purposes, as advertisement may be printed on the protecting cover on the rear wall or on the body *h*. The pocket glass can also be used as puzzle game in which case two or more floating bodies have to be brought into predetermined positions, or 20 into compartments arranged in the box.

I claim:—

1. A pocket glass as funny article consisting of a flat box, a rear wall of the box 25 formed by a mirror, a transparent partly reflecting front wall of said box, and a body enclosed between the front wall and the rear wall so that it moves over the reflecting surface when the pocket glass is turned end for end.

30. 2. A pocket glass as funny article consisting of a flat box, a mirror forming the rear wall of said box, a transparent front wall of said box, a mirror foil covering part of said transparent front wall, and a body enclosed between the front wall and the rear wall and normally hidden behind the reflecting part of said front wall so that it emerges out of this reflecting part of the front wall and moves over the reflecting surface of the rear wall when the 35 pocket glass is turned end for end.

40. 3. A pocket glass as funny article consisting of a flat box, a rear wall of said box formed by a mirror, a transparent front wall of said box, a mirror foil covering part of said transparent front wall, a body enclosed between the front wall and the rear wall and normally hidden behind the reflecting part of said front wall so that it emerges out of this reflecting part of the front wall and moves over the reflecting surface of the rear wall when the 45 pocket glass is turned end for end.

5. A pocket glass as funny article consisting of a flat box filled with a liquid, a rear wall of said box formed of a mirror, a transparent front wall of said box, a mirror foil covering part of said transparent front wall, a body of lighter specific gravity than the liquid in the box enclosed between said front wall and said rear wall and normally hidden behind the reflecting part of said front wall so that it emerges out of this reflecting part of the front wall and moves over the reflecting surface of the rear wall when the 50 pocket glass is turned end for end.

60. 6. A pocket glass as funny article consisting of a flat box filled with a liquid, a rear wall of said box formed of a mirror, a transparent front wall of said box, a mirror foil covering part of said transparent front wall, a body of lighter specific gravity than the liquid in the box enclosed between said front wall and said rear wall and normally hidden behind the reflecting part of said front wall so that it emerges out of this reflecting part of the front wall and moves over the reflecting surface of the rear wall when the pocket glass is turned end for end, and a thin almost invisible thread to which said body is 55 attached so that its movement is limited.

70. 7. A pocket glass as funny article consisting of a flat box filled with a liquid, a rear wall of said box formed of a mirror, a transparent front wall of said box, a mirror foil covering part of said transparent front wall, a body of lighter specific gravity than the liquid in the box enclosed between said front wall and said rear wall and normally hidden behind the reflecting part of said front wall so that it emerges out of this reflecting part of the front wall and moves over the reflecting surface of the rear wall when the pocket glass is turned end for end.

75. 8. A pocket glass as funny article consisting of a flat box filled with a liquid, a rear wall of said box formed of a mirror, a transparent front wall of said box, a mirror foil partly covering said transparent front wall, a body of heavier specific gravity than the liquid in the box enclosed between said front wall and said rear wall and normally hidden behind the reflecting part of said front wall so that it emerges out of this reflecting part of the front wall and moves over the reflecting surface of the rear wall when the pocket glass is turned end for end.

In testimony whereof I affix my signature.

AUGUST DICKMANN.
